(57) **ABSTRACT**

A wafer polishing apparatus includes a lower surface plate, an upper surface plate disposed over the lower surface plate, a carrier disposed between the lower surface plate and the upper surface plate and containing a wafer, and a lift unit lifting the carrier such that an upper surface of the carrier contacts a lower surface of the upper surface plate or lowering the carrier such that a lower surface of the carrier contacts an upper surface of the lower surface plate.

WAFER POLISHING APPARATUS

This application claims the benefit of Korean Patent Application No. 10-2014-0119969, filed on Sep. 11, 2014, which is hereby incorporated by reference as if fully set forth herein.

BACKGROUND OF THE INVENTION

Field of the Invention

Embodiments relate to a wafer polishing apparatus.

Discussion of the Related Art

A double side polishing (DSP) process is typically performed in such a way as to polish wafers by friction between a pad and wafers under the pressure of surface plates using slurry as an abrasive agent. The DSP process is capable of determining flatness of the wafers.

The DSP process may be implemented through mechano-chemical polishing, which incorporates both a chemical process of employing chemical action between slurry and the surface of the wafer and a mechanical process of employing friction between a pad and the wafer under the pressure of surface plates.

SUMMARY OF THE INVENTION

An embodiment provides a wafer polishing apparatus capable of improving the flatness of surfaces, rear surfaces and edge portions of polished wafers.

A wafer polishing apparatus according to an embodiment includes a lower surface plate, an upper surface plate disposed over the lower surface plate, a carrier disposed between the lower surface plate and the upper surface plate and containing a wafer, and a lift unit lifting the carrier such that an upper surface of the carrier contacts a lower surface of the upper surface plate or lowering the carrier such that a lower surface of the carrier contacts an upper surface of the lower surface plate.

The wafer polishing apparatus may further include a sun gear disposed at the center of the lower surface plate, and an internal gear disposed around the periphery of the lower surface plate, wherein the carrier may include a gear formed around an outer circumferential surface thereof and engaging with the sun gear and the internal gear, and the lift unit may lift or lower the sun gear and the internal gear.

The sun gear may include a first pin gear including a plurality of first pins, and a first support for supporting the plurality of first pins, wherein the lift unit may lift or lower the first support.

The internal gear may include a second pin gear including a plurality of second pins, and a second support for supporting the plurality of second pins, wherein the lift unit may lift or lower the second support.

The lift unit may concurrently lift or lower the first support and the second support.

The sun gear may further include first support rings projecting from outer circumferential surfaces of the plurality of respective first pins.

The first support rings may be provided at lower ends of the plurality of respective first pins and may contact an upper surface of the first support.

The first support rings may be provided at outer circumferential surface between the upper and lower ends of the plurality of respective first pins, and may be spaced apart from the upper and lower ends of the plurality of respective first pins.

2

The first support rings provided at the outer circumferential surfaces of two adjacent first pins of the plurality of first pins may be spaced apart from each other.

The internal gear may further include second support rings projecting from outer circumferential surfaces of the plurality of respective second pins.

The second support rings may be provided at lower ends of the plurality of respective second pins and may contact an upper surface of the second support.

10 The second support rings may be provided at outer circumferential surfaces of the plurality of respective second pins between the upper and lower ends of the plurality of respective second pins, and may be spaced apart from the upper and lower ends of the plurality of respective second pins.

15 The second support rings provided at the outer circumferential surfaces of two adjacent second pins of the plurality of second pins may be spaced apart from each other.

20 The lower surface plate may include a center hole, and the first support may be disposed in the center hole of the lower surface plate.

25 The lift unit may include a first lift part disposed under the first support to lift or lower the first support, and a second lift part disposed under the second support to lift or lower the second support.

30 Each of the first support rings may have a larger outer diameter than a width of the first support.

35 A wafer polishing apparatus according to another embodiment includes a lower surface plate, an upper surface plate disposed over the lower surface plate, a sun gear disposed at the center of the lower surface plate, an internal gear disposed around the periphery of the lower surface plate, a carrier disposed between the lower surface plate and the upper surface plate and containing a wafer, the carrier including a gear formed at an outer circumferential surface thereof and engaging with the sun gear and the internal gear, and a lift unit lifting the sun gear and the internal gear such that an upper surface of the carrier contacts a lower surface of the upper surface plate or lowering the sun gear and the internal gear such that a lower surface of the carrier contacts an upper surface of the lower surface plate.

40 The sun gear may include a first pin gear including a plurality of first pins, and a first support for supporting the plurality of first pins, wherein the internal gear may include a second pin gear including a plurality of second pins, and a second support for supporting the plurality of second pins, and wherein the lift unit may lift or lower the first support and the second support concurrently.

45 A wafer polishing apparatus according to a further embodiment includes a lower surface plate, an upper surface plate disposed over the lower surface plate, a carrier disposed between the lower surface plate and the upper surface plate and containing a wafer, a lift unit lifting the carrier such that an upper surface of the carrier contacts a lower surface of the upper surface plate or lowering the carrier such that a lower surface of the carrier contacts an upper surface of the lower surface plate, and a control unit controlling the lift unit to cause the carrier to be lifted or lowered, wherein the control unit controls the lift unit to cause a first surface of the carrier to contact one of a first surface of the upper surface plate and a first surface of the lower surface plate in a first polishing operation and to cause a second surface of the carrier to contact the other of the first surface of the upper surface plate and the first surface of the lower surface plate in a second polishing operation.

50 The control unit may control the lift unit to cause the first surface of the carrier to again contact the one of the first

surface of the upper surface plate and the first surface of the lower surface plate in a third polishing operation.

The embodiments may improve the flatness of surfaces, rear surfaces and edge portions of polished wafers.

It is to be understood that both the foregoing general description and the following detailed description of the embodiments are exemplary and explanatory and are intended to provide further explanation of the embodiments as claimed.

BRIEF DESCRIPTION OF THE DRAWINGS

The accompanying drawings, which are included to provide a further understanding of the embodiments and are incorporated in and constitute a part of this application, illustrate embodiments, and together with the description serve to explain the principle of the embodiments. In the drawings:

FIG. 1 is a cross-sectional view of a wafer polishing apparatus according to an embodiment;

FIG. 2 is a schematic perspective view showing an upper surface plate, a lower surface plate, an internal gear and a sun gear of the wafer polishing apparatus shown in FIG. 1;

FIG. 3A is an enlarged perspective view of an embodiment of the sun gear shown in FIG. 1;

FIG. 3B is an enlarged perspective view of another embodiment of the sun gear shown in FIG. 1;

FIG. 4 is a plan view of a gear of a carrier mounted on the first support ring shown in FIG. 3A;

FIG. 5A is an enlarged perspective view of an embodiment of the internal gear shown in FIG. 1;

FIG. 5B is an enlarged perspective view of another embodiment of the internal gear shown in FIG. 1;

FIG. 6 is a plan view of a gear of a carrier mounted on the second support ring shown in FIG. 5A;

FIGS. 7A and 7B are cross-sectional views showing a process of polishing wafers according to an embodiment;

FIGS. 8A to 8C are cross-sectional views showing a process of polishing wafers according to another embodiment;

FIG. 9A is a view illustrating positions of the carriers shown in FIG. 7A and FIG. 7B;

FIG. 9B is a view illustrating positions of the carriers shown in FIGS. 8A to 8C; and

FIG. 10 is a cross-sectional view of a conventional wafer polishing apparatus.

DETAILED DESCRIPTION OF THE INVENTION

Embodiments will become apparent from the following description of preferred embodiments with reference to the accompanying drawings. In the following description of embodiments, it will be understood that, when a layer (film), a region, a pattern or a structure is referred to as being 'on' or 'under' another element, it can be directly on/under the element, and one or more intervening elements may also be present therebetween. Here, the reference regarding 'on' or 'under' an element should be defined based on the drawings.

It should be understood that the size of the elements shown in the drawings may be exaggeratedly drawn or omitted for convenience and clarity of the explanation. Furthermore, it should be understood that the elements shown in the drawings are not drawn to scale, and the same reference numbers used throughout the different figures designate the same or similar components.

FIG. 1 is a cross-sectional view of a wafer polishing apparatus 100 according to an embodiment, and FIG. 2 is a schematic perspective view showing an upper surface plate, a lower surface plate, an internal gear and a sun gear of the wafer polishing apparatus shown in FIG. 1.

Referring to FIGS. 1 and 2, the wafer polishing apparatus 100 may include a lower surface plate 110, a lower surface plate rotator 120, a support 130, an upper surface plate 140, an upper surface plate rotator 150, a sun gear 160, an internal gear 170, one or more carriers 180-1 and 180-2, a lift unit 190, and a control unit 200.

The lower surface plate 110 may be embodied as an annular plate that supports wafers W1 and W2 loaded on the one or more carriers 180-1 and 180-2 and has a center hole 111. The lower surface plate 110 may include a polishing pad mounted on the upper surface thereof to polish the wafers.

The lower surface plate rotator 120 is disposed under the lower surface plate 110 to rotate it.

The lower surface plate rotator 120 may include a first rotating shaft 122 for rotating the lower surface plate 110. The first rotating shaft 122 may be connected to a lower surface of the lower surface plate 110 so as to support the lower surface plate 110 and to rotate the lower surface plate 110 in a first direction.

For example, the first rotating shaft 122 may be rotated in the first direction (e.g. counterclockwise) by the rotation of a driving motor (not shown), and thus the lower surface plate 110 may be rotated in the first direction (e.g. counterclockwise) by the rotational force of the first rotating shaft 122.

The upper surface plate 140 may be disposed over the lower surface plate 110 such that the lower surface of the upper surface plate 140 faces the upper surface of the lower surface plate 110. The upper surface plate 140 may be embodied as an annular plate having a center hole. The upper surface plate 140 may include a polishing pad attached to the lower surface thereof to polish wafers.

The upper surface plate rotator 150 may rotate the upper surface plate 140 to further move the upper surface plate 140 vertically.

The upper surface plate rotator 150 may include a second rotating shaft 152 connected to the upper surface plate 140 to rotate the upper surface plate 140.

The second rotating shaft 152 may be connected to the upper surface of the upper surface plate 140 to rotate the upper surface plate 140 in the second direction. The second rotating shaft 152 may vertically move the upper surface plate 140 to control the weight of the upper surface plate 140 applied to the wafers W1 and W2 loaded on the one or more carriers 180-1 and 180-2. The second direction may be the direction opposite to the first direction (e.g. the clockwise direction).

For example, the second rotating shaft 152 may be connected to a driving motor (not shown). The second rotating shaft 152 may be rotated in the second direction by the rotation of the driving motor, and the upper surface plate 140 may be rotated in the second direction by the rotational force of the second rotating shaft 152.

The second rotating shaft 152 may be connected to a pneumatic or hydraulic cylinder (not shown), and the weight of the upper surface plate 140 may be controlled by the pneumatic or hydraulic cylinder. During polishing, the upper surface plate 140 may apply pressure to the wafers W1 and W2 loaded on the one or more carriers 180-1 and 180-2. For example, the weight of the upper surface plate 140 applied to the wafers W1 and W2 loaded on the one or more carriers 180-1 and 180-2 may be controlled by the pneumatic or hydraulic cylinder (not shown).

The sun gear **160** may include a plurality of first pins **162-1** to **162-m** (where m is a natural number satisfying $m > 1$), and a first support **161** for supporting the plurality of first pins **162-1** to **162-m**.

The first support **161** is disposed in the center hole **111** of the lower surface plate **110**, and may be embodied as an annular plate. However, the shape of the first support **161** is not limited thereto. For example, although the first support **161** may have a ring shape, it is not limited thereto.

The plurality of first pins **162-1** to **162-m** may be arranged in a line with intervals therebetween. The sun gear **160** shown in FIG. 2 may include a pin gear including the plurality of first pins **162-1** to **162-m** and the first support **161**.

The internal gear **170** may be positioned around periphery of the lower surface plate **110**. For example, the internal gear **170** may be embodied as an annular plate whose inner circumferential surface surrounds the outer circumferential surface of the lower surface plate **110**.

The internal gear **170** may include a plurality of second pins **172-1** to **172-n** (where n is a natural number satisfying $n > 1$), and a second support **171** for supporting the plurality of second pins **172-1** to **172-n**.

The second support **171** may be embodied as an annular plate disposed around the periphery of the lower surface plate **110**. For example, although the second support **171** may have a ring shape, it is not limited thereto.

The plurality of second pins **172-1** to **172-n** may be arranged in a line on the upper surface of the second support **171**, with intervals therebetween. The internal gear **170** shown in FIG. 2 may include a pin gear including the plurality of second pins **172-1** to **172-n**, and the second support **171**.

The one or more carriers **180-1** and **180-2** are disposed between the upper surface of the lower surface plate **110** and the lower surface of the upper surface plate **140**, in which the wafers to be polished **W1** and **W2** are received or loaded.

Each of the one or more carriers **180-1** and **180-2** may include a carrier body **180** (see FIG. 4) having a wafer mount hole **183** in which the wafer **W1** or **W2** is received and at least one slurry hole **184** which is spaced apart from the wafer mount hole **183** and through which slurry passes, and a gear **188** provided at the outer circumferential surface of the carrier body **180**.

The slurry holes **184** may have the same diameter or different diameters, and may have a smaller diameter than that of the wafer mount hole **183**.

The one or more carriers **180-1** and **180-2** may be made of epoxy glass, SUS, urethane, ceramics, or polymer.

Although the carrier body **180** may have a disc shape, it is not limited thereto.

The gear **188** formed at the outer circumferential surface of the carrier **180-1** or **180-2** may engage with both the first pins **162-1** to **162-m** of the sun gear **160** and the second pins **172-1** to **172-n** of the internal gear **170**. The one or more carriers **180-1** and **180-2** may engage with both the sun gear **160** and the internal gear **170** so as to be rotated thereby during the polishing process.

The lift unit **190** may be configured to lift or lower the one or more carriers **180-1** and **180-2** disposed on the upper surface of the lower surface plate **110**.

The lift unit **190** may lift or lower the sun gear **160** and the internal gear **170**. For example, the lift unit **190** may lift or lower the sun gear **160** and the internal gear **170** concurrently.

The lift unit **190** may also lift or lower the sun gear **160** and the internal gear **170** while polishing wafers received in

the carriers **180-1** and **180-2**, which are rotated between the sun gear **160** and the internal gear **170** due to the rotation of the upper surface plate **140** and the lower surface plate **110**.

The lift unit **190** may include first lift parts **192-1** and **192-2** for lifting or lowering the sun gear **160**, and second lift parts **194-1** and **194-2** for lifting or lowering the internal gear **170**.

For example, the first lift parts **192-1** and **192-2** may be disposed under the first support **161** to lift or lower the first support **161**.

The first lift parts **192-1** and **192-2** may include one or more first lift parts. For example, the first lift parts **192-1** and **192-2** may include a plurality of first lift parts, and the plurality of first lift parts may concurrently lift or lower different portions of the first support **161**.

The second lift parts **194-1** and **194-2** may be disposed under the second support **171** to lift or lower the second support **171**.

The second lift parts **194-1** and **194-2** may include one or more second lift parts. For example, the second lift parts **194-1** and **194-2** may include a plurality of second lift parts, and the plurality of second lift parts may concurrently lift or lower the different portions of the second support **171**.

The first lift parts **192-1** and **192-2** and the second lift parts **194-1** and **194-2** may each include a pneumatic or hydraulic cylinder, and may lift or lower the first support **161** and the second support **171** by using pressure supplied from the pneumatic or hydraulic cylinder.

In another embodiment, each of the first lift parts **192-1** and **192-2** and the second lift parts **194-1** and **194-2** may include an up-down motor that is configured to convert the rotational force generated by driving the motor into a vertical linear movement, and thus lifting or lowering the first support **161** and the second support **171** by the vertical linear movement.

As the first support **161** is lifted or lowered, the first pins **162-1** to **162-m** secured to the first support **161** and the second pins **172-1** to **172-n** secured to the second support **171** may also be lifted or lowered therewith.

Furthermore, as the first support **161** and the second support **171** are lifted or lowered, the one or more carriers **180-1** and **180-2** engaging with the first pins **162-1** to **162-m** and the second pins **172-1** to **172-n** may also be lifted or lowered therewith.

By virtue of the first lift parts **192-1** and **192-2** and the second lift part **194-1** and **194-2**, the first support **161** and the second support **171** may be lifted or lowered therewith, thus lifting or lowering the one or more carriers **180-1** and **180-2**.

Even though the one or more carriers **180-1** and **180-2** are lifted or lowered, the wafers **W1** and **W2** received in the wafer mount holes **183** are not lifted or lowered but are kept on the lower surface plate **110**.

FIG. 3A is an enlarged perspective view of an embodiment **160-1** of the sun gear shown in FIG. 1.

Referring to FIG. 3A, the sun gear **160-1** may further include a first support ring **310** projecting outward from the outer circumferential surface of each of the first pins **162-1** to **162-m**.

The first support ring **310** may be provided at the lower end of each of the first pins **162-1** to **162-m** so as to contact the upper surface of the first support **161**.

The first support ring **310** serves as a shoulder support for supporting the gear **188** formed on the outer circumferential surface of each of the carriers **180-1** and **180-2**.

The first support rings **310** provided at adjacent first pins may be spaced apart from each other. In order to reliably support the gear **188** formed on the outer circumferential

surface of each of the carriers **180-1** and **180-2**, the diameter D1 of the outer circumferential surface of the first support ring **310** may be greater than the width P1 of the first support **161**. However, this embodiment is not limited thereto.

FIG. 4 is a plan view of the gear **188** of the carrier **180-1** placed on the first support ring **310** shown in FIG. 3A.

Referring to FIG. 4, the first support ring **310** increases the area of contact with the gear **188** formed on the outer circumferential surface of each of the carriers **180-1** and **180-2**. Consequently, the first support ring **310** may reliably support the carriers **180-1** and **180-2** when the carriers **180-1** and **180-2** are lifted or lowered by means of the lift unit **190**.

FIG. 3B is an enlarged perspective view of another embodiment **160-2** of the sun gear shown in FIG. 1.

Referring to FIG. 3B, the sun gear **160-2** may further include a first support ring **320** projecting outward from an outer circumferential surface portion positioned between the upper and lower ends of each of the first pins **162-1** to **162-m**.

The first support ring **320** may be disposed to be spaced apart from the upper and lower ends of the first pin (for example, **162-1**). Although the diameter of the first support ring **320** may be greater than the width of the first support **161**, it is not limited thereto.

FIG. 5A is an enlarged perspective view of an embodiment **170-1** of the internal gear shown in FIG. 1.

Referring to FIG. 5A, the internal gear **170-1** may further include a second support ring **330** projecting outward from the outer circumferential surface of each of the second pins **172-1** to **172-n**.

The second support ring **330** may be provided at the lower end of each of the second pins **172-1** to **172-n**, and may contact the upper surface of the second support **171**.

The second support ring **330** serves as a shoulder support for supporting the gear **188** formed on the outer circumferential surface of each of the carriers **180-1** and **180-2**.

The second support rings **330**, provided at two of the second pins that are adjacent to each other, may be spaced apart from each other. In order to reliably support the gear **188** formed on the outer circumferential surface of each of the carriers **180-1** and **180-2**, the diameter D1 of the outer circumferential surface of the second support ring **330** may be greater than the width P1 of the second support **171**. However, the embodiment is not limited thereto.

FIG. 6 is a plan view of the gear **188** of the carrier **180-1** placed on the second support ring **330** shown in FIG. 5A.

Referring to FIG. 6, the second support ring **330** increases the area of contact with the gear **188** formed on the outer circumferential surface of each of the carriers **180-1** and **180-2**. Consequently, the second support ring **330** may reliably support the carriers **180-1** and **180-2** when the carriers **180-1** and **180-2** are lifted or lowered by means of the lift unit **190**.

FIG. 5B is an enlarged perspective view of another embodiment **170-2** of the internal gear shown in FIG. 1.

Referring to FIG. 5B, the internal gear **170-2** may further include a second support ring **340** projecting outward from the outer circumferential surface portion positioned between the upper and lower ends of each of the second pins **172-1** to **172-n**.

The second support ring **340** may be disposed to be spaced apart from the upper and lower ends of the second pin (for example, **172-1**). Although the diameter of the second support ring **340** may be greater than the width of the second support **171**, it is not limited thereto.

The control unit **200** controls the lift unit **190** to cause the one or more carriers **180-1** and **180-2** to be lifted or lowered.

For example, the control unit **200** may control the first lift parts **192-1** and **192-2** to cause the first support **161** to be lifted or lowered, and may control the second support **171** to cause the second lift parts **194-1** and **194-2** to be lifted or lowered.

FIG. 10 is a cross-sectional view of a typical wafer polishing apparatus.

Referring to FIG. 10, the conventional process of polishing wafers **W1** and **W2** employs a construction such that carriers **30-1** and **30-2**, which contain the wafers **W1** and **W2** received therein, are positioned between a sun gear **40** and an internal gear **50** to engage therewith and are mounted on the upper surface of a lower surface plate **10**, thus polishing the wafers **W1** and **W2** using the upper surface plate **20** and the lower surface plate **10**.

Owing to the difference between the thickness of the carriers **30-1** and **30-2** and the initial thickness of the wafers not subjected to polishing, the working load **70** applied to the edge of the upper surface of the wafer that contacts the upper surface plate **20** is increased to be higher than the working load applied to other portions of the upper surface of the wafer, and thus the flatness of the upper surface of the wafer may be deteriorated.

FIGS. 7A and 7B illustrate the process of polishing wafers according to an embodiment.

The process of polishing wafers according to the embodiment may include a first polishing operation, shown in FIG. 7A, and a second polishing operation, shown in FIG. 7B.

Referring to FIG. 7A, the one or more carriers **180-1** and **180-2** containing the wafers **W1** and **W2** are mounted on the upper surface of the lower surface plate **110**.

At this point, the initial thickness (t1) of the wafers not subjected to polishing may be different from the thickness (t2) of the carriers **180-1** and **180-2**. For example, the initial thickness (t1) of the wafers **W1** and **W2** not subjected to polishing may be greater than the thickness (t2) of at least one of the carriers **180-1** and **180-2** ($t1 > t2$).

Owing to the difference between the initial thickness t1 of the wafers not subjected to polishing and the thickness (t2) of the carriers **180-1** and **180-2**, the upper surfaces of the wafers disposed on the upper surface of the lower surface plate **110** may be positioned to be higher than the upper surfaces of the carriers **180-1** and **180-2**.

In other words, when the lower surface of the upper surface plate **140** is caused to contact the upper surfaces of the wafers **W1** and **W2** received in the carriers **180-1** and **180-2**, the upper surfaces of the wafers may contact the lower surface of the upper surface plate **140**, but the upper surfaces of the carriers **180-1** and **180-2** may be spaced apart from the lower surface of the upper surface plate **140**.

Subsequently, the lower surface of the upper surface plate **140** is caused to contact the upper surfaces of the wafers **W1** and **W2** received in the carriers **180-1** and **180-2**.

The one or more carriers **180-1** and **180-2** are lifted by means of the lift unit **190** such that the upper surfaces of the one or more carriers **180-1** and **180-2** mounted on the lower surface plate **110** come into contact with the lower surface of the upper surface plate **140** and the lower surfaces of the carriers **180-1** and **180-2** are spaced apart from the upper surface of the lower surface plate **110**.

For example, lifting the first support **161** and the second support **171** by the first and second lift parts **192-1**, **192-2**, **194-1** and **194-2** causes the upper surfaces of the one or more carriers **180-1** and **180-2** mounted on the lower surface plate **110** to come into contact with the lower surface of the upper surface plate **140** while causing the lower surfaces of

the carriers **180-1** and **180-2** to be spaced apart from the upper surface of the lower surface plate **110**.

The wafers **W1** and **W2** received in the one or more carriers **180-1** and **180-2** are polished while the upper surfaces of the one or more carriers **180-1** and **180-2** are in contact with the lower surface of the upper surface plate **140**.

The first polishing operation may be performed until the polished wafers have a first thickness. For example, the first thickness may be in a range of 10% to 60% of the difference between the initial thickness (t_1) of the wafers not subjected to polishing and the desired final target thickness of the wafers **W1** and **W2**.

As shown in FIG. 7A, since the upper surfaces of the carriers **180-1** and **180-2** contact the lower surface of the upper surface plate **140** in the first polishing operation, the working load **710** applied to the edges of the upper surfaces of the wafers **W1** and **W2** is lower than the working load **720** applied to the edges of the lower surfaces of the wafers **W1** and **W2**.

The term "working load" used herein may refer to the force applied to the wafers **W1** and **W2** by the upper surface plate **140**. In some cases, when a first polishing pad is mounted on the upper surface plate **140** and a second polishing pad is mounted on the lower surface plate **110**, the working load may refer to the frictional load between the wafers **W1** and **W2** and the first and second polishing pads.

Since the working load **710** applied to the edges of the upper surfaces of the wafers **W1** and **W2** is lower than the working load **70** applied to the edges of the upper surfaces of the wafers shown in FIG. 10, the flatness of the upper surfaces of the wafers **W1** and **W2** that have been polished in the first polishing operation may be improved.

As shown in FIG. 7B, after the first polishing operation, the one or more carriers **180-1** and **180-2** are lowered by means of the lift unit **190** such that the lower surfaces of the one or more carriers **180-1** and **180-2** come into contact with the upper surface of the lower surface plate **110**.

For example, lowering the first support **161** and the second support **171** by the first and second lift units **192-1**, **192-2**, **194-1** and **194-2** causes the lower surfaces of the one or more carriers **180-1** and **180-2** to come into contact with the upper surface of the lower surface plate **110**.

The wafers **W1** and **W2** that were polished in the first polishing operation are secondly polished to the desired final target thickness of the wafers **W1** and **W2** while the lower surfaces of the one or more carriers **180-1** and **180-2** are in contact with the upper surface of the lower surface plate **110**.

For example, the wafers **W1** and **W2** that were polished in the first polishing operation may be secondly polished by the difference between the first thickness and the final target thickness.

Since the lower surfaces of the carriers **180-1** and **180-2** are in contact with the upper surface of the lower surface plate **110** in the second polishing operation, the working load **720-1** applied to the edges of the lower surfaces of the wafers **W1** and **W2** is lower than the working load **720** applied to the edges of the lower surfaces of the wafers **W1** and **W2** in the first polishing operation.

Since the working load **720-1** applied to the edges of the lower surfaces of the wafers **W1** and **W2** in the second polishing operation is decreased to be lower than that in the first polishing operation, the flatness of the lower surfaces of the wafers **W1** and **W2** may be improved.

The embodiment may improve the flatness of the upper surfaces of the wafers **W1** and **W2** by lifting the carriers **180-1** and **180-2** to cause the upper surfaces of the carriers **180-1** and **180-2** to contact the lower surface of the upper

surface plate **140** in the first polishing operation. Furthermore, the embodiment may improve the flatness of the lower surfaces of the wafers **W1** and **W2** by lowering the carriers **180-1** and **180-2** to cause the lower surfaces of the carriers **180-1** and **180-2** to contact the upper surface of the lower surface plate **110** in the second polishing operation.

FIGS. 8A to 8C illustrate the process of polishing wafers according to another embodiment.

The process of polishing wafers according to this embodiment may include a first polishing operation, shown in FIG. 8A, a second polishing operation, shown in FIG. 8B, and a third polishing operation, shown in FIG. 8C.

For example, in the first polishing operation, the lift unit **190** may be controlled to cause the carriers **180-1** and **180-2** to be moved such that first surfaces of the carriers **180-1** and **180-2** come into contact with one of a first surface of the upper surface plate **140** and a first surface of the lower surface plate **110**.

In the second polishing operation, the lift unit **190** may be controlled to cause the carriers **180-1** and **180-2** to be moved such that second surfaces of the carriers **180-1** and **180-2** come into contact with the other of the first surface of the upper surface plate **140** and the first surface of the lower surface plate **110**.

In the third polishing operation, the lift unit **190** is controlled to cause the carriers **180-1** and **180-2** to be moved such that the first surfaces of the carriers **180-1** and **180-2** again come into contact with the one of the first surface of the upper surface plate **140** and the first surface of the lower surface plate **110**.

The first surfaces of the carriers **180-1** and **180-2** may be opposite to the second surfaces of the carriers **180-1** and **180-2**. When the first surface of the upper surface plate **140** is the upper surface thereof, the first surface of the lower surface plate **110** may be the lower surface thereof, and vice versa. The moving direction of the carriers **180-1** and **180-2** in the first polishing operation may be opposite to the moving direction of the carriers **180-1** and **180-2** in the second polishing operation. Furthermore, the moving direction of the carriers **180-1** and **180-2** in the third polishing operation may be opposite to the moving direction of the carriers **180-1** and **180-2** in the second polishing operation.

Referring to FIG. 8A, positions of the carriers **180-1** and **180-2** are controlled by the lift unit **190** such that the lower surfaces of the carriers come into contact with the upper surface of the lower surface plate **110**.

For example, the first support **161** and the second support **171** may be lowered by the first and second parts **192-1**, **192-2**, **194-1** and **194-2** such that the lower surfaces of the carriers **180-1** and **180-2** come into contact with the upper surface of the lower surface plate **110**.

The wafers **W1** and **W2** received in the one or more carriers **180-1** and **180-2** are first polished while the lower surfaces of the one or more carriers **180-1** and **180-2** are in contact with the upper surface of the lower surface plate **110**.

The first polishing operation may be performed until the polished wafers have a second thickness. For example, the second thickness may be in a range of 10% to 80% of the difference between the initial thickness (t_1) of the wafers not subjected to polishing and the desired final target thickness of the wafers **W1** and **W2**.

Since the working load **820** applied to the edges of the lower surfaces of the wafers **W1** and **W2** is lower than the working load **810** applied to the edges of the upper surfaces of the wafers **W1** and **W2** in the first polishing operation, the flatness of the lower surfaces of the wafers may be improved compared to the upper surfaces of the wafers.

11

Referring to the FIG. 8B, after the first polishing operation, the one or more carriers **180-1** and **180-2** are lifted by the lift unit **190** such that the upper surfaces of the one or more carriers **180-1** and **180-2** come into contact with the lower surface of the upper surface plate **140** whereas the lower surfaces of the carriers **180-1** and **180-2** are spaced apart from the upper surface of the lower surface plate **110**.

The wafers **W1** and **W2** are secondly polished while the upper surfaces of the one or more carriers **180-1** and **180-2** are in contact with the lower surface of the upper surface plate **140**. The second polishing operation may be performed until the wafers **W1** and **W2** have a third thickness. For example, the third thickness may be in a range of 10% to 70% of the difference between the third thickness and the second thickness.

Since the working load applied to the edges of the upper surfaces of the wafers **W1** and **W2** in the second polishing operation is lower than that in the first polishing operation, the flatness of the upper surfaces of the wafers may be improved compared to that in the first polishing operation.

The working load **820-1** applied to the edges of the lower surfaces of the wafers **W1** and **W2** is higher than that in the first polishing operation but may be lower than the working load applied to the edges of the lower surfaces of the wafers shown in FIG. 7A because the difference between the thickness of the wafers and the thickness of the carriers is decreased. Accordingly, the flatness of the lower surfaces of the wafers in the second polishing operation may be improved compared to the flatness of the lower surfaces of the wafers shown in FIG. 7A.

Referring to FIG. 8C, after the second polishing operation, the carriers **180-1** and **180-2** are lowered by the lift unit **190** such that the lower surfaces of the carriers **180-1** and **180-2** come into contact with the upper surface of the lower surface plate **110**.

The wafers **W1** and **W2** that were secondly polished are thirdly polished while the lower surfaces of the carriers **180-1** and **180-2** are in contact with the upper surface of the lower surface plate **110** until the wafers **W1** and **W2** have the final target thickness.

In the third polishing operation, since the lower surfaces of the carriers **180-1** and **180-2** are in contact with the upper surface of the lower surface plate **110**, the working load **820-1** applied to the edges of the wafers that were secondly polished may be decreased, and thus the flatness of the lower surfaces of the wafers **W1** and **W2** may be improved.

In addition, since the difference between the thickness of the wafers **W1** and **W2** and the thickness of the carriers **180-1** and **180-2** is further decreased, the difference between the working load of the edges of the upper surfaces of the wafers and the working load of other portions of the upper surfaces of the wafers may be decreased, and thus the flatness of the upper surfaces of the wafers may also be improved.

FIG. 9A illustrates the positions of the carriers shown in FIGS. 7A and 7B.

In the drawing, the x axis denotes the polishing time, and the y axis denotes the height of the carriers.

Referring to FIG. 9A, in the first polishing operation (section of 0-t1), the one or more carriers **180-1** and **180-2** may be lifted, and the height of the upper surfaces of the carriers **180-1** and **180-2** from the upper surface of the lower surface plate **110** may be a first height (H1). For example, the first height (H1) may be the distance from the upper surface of the lower surface plate **110** to the upper surfaces

12

of the carriers **180-1** and **180-2** when the upper surfaces of the carriers **180-1** and **180-2** contact the lower surface of the upper surface plate **140**.

In the second polishing operation (section of t1-t2), the one or more carriers **180-1** and **180-2** may be lowered, and the height of the upper surfaces of the carriers **180-1** and **180-2** from the upper surface of the lower surface plate **110** may be a second height (H2). For example, the second height (H2) may be the distance from the upper surface of the lower surface plate **110** to the upper surfaces of the carriers **180-1** and **180-2** when the lower surfaces of the carriers **180-1** and **180-2** contact the upper surface of the lower surface plate **110**.

FIG. 9B illustrates the positions of the carriers shown in FIGS. 8A and 8B.

Referring to FIG. 9B, in the first polishing operation (section of 0-t3), the height of the upper surfaces of the carriers **180-1** and **180-2** from the upper surface of the lower surface plate **110** may be a second height (H2).

In the second polishing operation (section of t3-t4), the one or more carriers **180-1** and **180-2** may be lifted, and the height of the upper surfaces of the carriers **180-1** and **180-2** from the upper surface of the lower surface plate **110** may be a third height (H3). For example, the third height (H3) may be the distance from the upper surface of the lower surface plate **110** to the upper surfaces of the carriers **180-1** and **180-2** when the upper surfaces of the carriers **180-1** and **180-2**, which contain the secondly polished wafers, contact the lower surface of the upper surface plate **140**.

In the third polishing operation (section of t4-t2), the one or more carriers **180-1** and **180-2** may be lowered, and the height of the upper surfaces of the carriers **180-1** and **180-2** from the upper surface of the lower surface plate **110** may be a second height (H2).

The embodiments may improve the flatness of surfaces, rear surfaces and edge portions of polished wafers by reducing the difference between the upper surfaces of the carriers **180-1** and **180-2** and the upper surfaces of the wafers **W1** and **W2** and the difference between the lower surfaces of the carriers **180-1** and **180-2** and the lower surfaces of the wafers **W1** and **W2** by lifting and lowering the carriers **180-1** and **180-2**.

Although embodiments have been described with reference to a number of illustrative embodiments thereof, it should be understood that numerous other modifications and embodiments can be devised by those skilled in the art that will fall within the spirit and scope of the principles of this disclosure. More particularly, various variations and modifications are possible in the component parts and/or arrangements of the subject combination arrangement within the scope of the disclosure, the drawings and the appended claims. In addition to variations and modifications in the component parts and/or arrangements, alternative uses will also be apparent to those skilled in the art.

What is claimed is:

1. A wafer polishing apparatus comprising:
a lower surface plate;
an upper surface plate disposed over the lower surface plate;
a sun gear disposed at a center of the lower surface plate;
an internal gear disposed around the periphery of the lower surface plate;
a carrier disposed between the lower surface plate and the upper surface plate for containing a wafer, the carrier including a gear formed around an outer circumferential surface thereof and engaging with the sun gear and the internal gear; and

13

a lift unit configured to lift the sun gear and the internal gear such that an upper surface of the carrier contacts a lower surface of the upper surface plate or configured to lower the sun gear and the internal gear such that a lower surface of the carrier contacts an upper surface of the lower surface plate.

2. The wafer polishing apparatus according to claim 1, wherein the sun gear comprises:

a first pin gear including a plurality of first pins; and a first support for supporting the plurality of first pins, wherein the lift unit lifts or lowers the first support.

3. The wafer polishing apparatus according to claim 2, wherein the internal gear comprises:

a second pin gear including a plurality of second pins; and a second support for supporting the plurality of second pins,

wherein the lift unit lifts or lowers the second support.

4. The wafer polishing apparatus according to claim 3, wherein the lift unit concurrently lifts or lowers the first support and the second support.

5. The wafer polishing apparatus according to claim 3, wherein the internal gear further comprises second support rings projecting from outer circumferential surfaces of the plurality of second pins.

6. The wafer polishing apparatus according to claim 5, wherein the second support rings are provided at lower ends of the plurality of respective second pins and contact an upper surface of the second support.

7. The wafer polishing apparatus according to claim 5, wherein the second support rings are provided at outer circumferential surfaces of the plurality of respective second pins between the upper and lower ends of the plurality of respective second pins and are spaced apart from the upper and lower ends of the plurality of respective second pins.

8. The wafer polishing apparatus according to claim 5, wherein the second support rings provided at the outer circumferential surfaces of two adjacent second pins of the plurality of second pins are spaced apart from each other.

9. The wafer polishing apparatus according to claim 3, wherein the lift unit comprises:

a first lift part disposed under the first support to lift or lower the first support; and

a second lift part disposed under the second support to lift or lower the second support.

10. The wafer polishing apparatus according to claim 2, wherein the sun gear further comprises first support rings projecting from outer circumferential surfaces of the plurality of first pins.

11. The wafer polishing apparatus according to claim 10, wherein the first support rings are provided at lower ends of the plurality of respective first pins and contact an upper surface of the first support.

14

12. The wafer polishing apparatus according to claim 10, wherein the first support rings are provided at outer circumferential surfaces between the upper and lower ends of the plurality of respective first pins and are spaced apart from the upper and lower ends of the plurality of respective first pins.

13. The wafer polishing apparatus according to claim 10, wherein the first support rings provided at the outer circumferential surfaces of two adjacent first pins of the plurality of first pins are spaced apart from each other.

14. The wafer polishing apparatus according to claim 10, wherein each of the first support rings has a larger outer diameter than a width of the first support.

15. The wafer polishing apparatus according to claim 2, wherein the lower surface plate includes a center hole, and the first support is disposed in the center hole of the lower surface plate.

16. A wafer polishing apparatus comprising:
a lower surface plate;
an upper surface plate disposed over the lower surface plate;

a sun gear disposed at a center of the lower surface plate; an internal gear disposed around the periphery of the lower surface plate;

a carrier disposed between the lower surface plate and the upper surface plate and containing a wafer, the carrier including a gear formed around an outer circumferential surface thereof and engaging with the sun gear and the internal gear;

a lift unit configured to lift the sun gear and the internal gear such that an upper surface of the carrier contacts a lower surface of the upper surface plate or configured to lower the sun gear and the internal gear such that a lower surface of the carrier contacts an upper surface of the lower surface plate; and

a control unit to control the lift unit to cause the carrier to be lifted or lowered,

wherein the control unit controls the lift unit to cause a first surface of the carrier to contact one of a first surface of the upper surface plate and a first surface of the lower surface plate in a first polishing operation and to cause a second surface of the carrier to contact the other of the first surface of the upper surface plate and the first surface of the lower surface plate in a second polishing operation.

17. The wafer polishing apparatus according to claim 16, wherein the control unit controls the lift unit to cause the first surface of the carrier to again contact the one of the first surface of the upper surface plate and the first surface of the lower surface plate in a third polishing operation.
